ROCK DRILL

Frank F. Graham, Cardiff, Md., assignor to Pe-
ton du Pont, Incorporated, a corporation of
Delaware

Application December 13, 1933, Serial No. 702,107

7 Claims. (Cl. 255—64)

My invention pertains to improvements in drills, and more particularly to that class of drills adapted for use in rock drilling, mining and the like.

5 Heretofore, drills of the class specified included a suitable rod, one end being adapted for attachment to suitable power operating mechanism, while the other end of the rod carried a drill bit. A passage extended axially through the rod and 10 drill bit and when the drill was in operation, air or water under pressure could be passed through this axial passage for the purpose of blowing or washing out the rock dust from the hole being drilled.

15 I have found from experience that when a drill of the above described construction rotates in the rock bed, a small round core remains uncut and is driven upwardly into the axial passage, plugging the same. This is a source of considerable trouble because it necessitates the removal of the 20 drill from the rock bed so that the passage may be cleared. Failure to maintain a clear passage will greatly reduce the cutting speed of the drill because of the presence of the rock dust and chips, which cannot be blown or washed from the drilled 25 hole until air or water is forced through the axial passage.

30 I have devised an extremely simple and efficient means for obviating these difficulties and accordingly this is the main object of my invention.

35 A more specific object of this invention is the provision of a drill, including a rod, one end of which is adapted to be connected to an operating means and the other end of which carries a drill bit having integral cutting edges; the drill rod is provided with an axial passage therethrough and the drill bit is also provided with a passage communicating with the axial passage and opening through the drill bit eccentrically with reference 40 to the axial passage of the drill rod but being included between the integral cutting edges.

45 Other objects and advantages of my invention will become apparent as the following description is read in connection with the accompanying drawing, in which

Figure 1 is a central vertical section of my improved rock drill showing a portion of the operating mechanism therefor in similar section;

Figure 2 is a view taken on the line 2—2 of 50 Figure 1;

Figure 3 is a perspective view of the lower end of the improved drill;

Figure 4 is a view similar to Figure 3 with portions cut away to illustrate the invention more 55 clearly;

Figure 5 is a view similar to Figure 3 showing a modification of my invention; and

Figure 6 is a view similar to Figure 4 showing a further modification.

In the drawing, 10 designates the rock drill 5 as a whole, which is preferably of the "Jackhammer" type and includes a casing 11 for housing the power operating mechanism of the drill. Projecting outwardly beyond the casing 11 is a drill rod 12 having an angular end 13 fitted into a chuck 14 which transmits short, hammer-like strokes and also a rotating motion to the drill rod 12. Since the mechanism which produces this motion is of a well known construction and forms no part 15 of my invention, detail description thereof is not necessary.

At its lower end, the drill rod 12 carries a bit 15 which includes a cylindrical body portion 16 having formed integrally therewith a plurality of cutting edges such as 17. Each cutting edge 17 is formed by the intersection of the substantially triangular shaped side faces 18 which converge toward the axis of the bit 15. In Figures 1 to 4, and 6, these cutting edges do not intersect at a common point but terminate somewhat short of 25 one another, providing a recess 9 in order that resharpening of these bits will be facilitated. If desired, the apices of the triangular faces may intersect at a common point P, as shown in Figure 5, and in this manner the bit 15 will then have an axial cutting point and also increased strength 30 at this point. However, it is preferable that the recess 9 be formed, for the purpose which will hereinafter appear.

35 Preferably, the cutting edges 17 all lie in a common plane and their outer portions 19 extend beyond the limits of the body portion 16 and the drill rod 12 in order that the hole 20 which is drilled in the rock bed 21 may be somewhat larger than this body portion and drill rod. This construction permits rock dust and chips to be freely 40 ejected from the drilled hole 20 in a manner which will be fully described.

The bit 15 is detachably secured to the lower 45 end of the drill rod 12 by means of the interengaging screw threads 22, which are formed at the lower end of the drill rod and within the body portion 16. These screw threads are of special form and permit the hammer blow of the drill 10 to be transmitted to the cutting edges 17 directly 50 through the end face 23 of the rod 12 which abuts the seat 24 of the bit 15 and not through the screw threads.

Drilled axially through the rod 12 is a passage 55 which may extend into the bit 15 below the gg

seat 24. Between the triangular faces of the adjacent cutting edges 17 I drill a hole or passage 26 which intersects the passage 25 and opens exteriorly between the cutting edges so as to be 5 eccentric with reference to the axis of the drill rod 12. I have found that best results are gained when the holes 26 open exteriorly closely adjacent the axis of the bit 15 so that the compressed air when forced through these holes will impinge 10 directly on the bottom of the hole being drilled to effectively clear the same of rock dust and chips. In other words, it is preferable that the holes 26 be drilled in a manner so that the extended axis of each hole will intersect the plane 15 of the cutting edges 17 within the limits of their outer portions 19. The undercut or recess 9 forms a space between the bottom of the drilled hole and the end of the drill through which space 20 stone chips may be blown by the spreading action of the fluid emerging from the angular holes 26, from the under side of the drill bit.

Figure 6 shows a further modification of my invention in which the hammer blow of the drill 10 is transmitted to the cutting edges 17 through 25 the abutting shoulders 27 and 28 of the drill rod 29 and bit 30, respectively. That portion of the bit 30 immediately beneath the end face 31 of the rod 29 is relieved as at 32 and forms with the end face 31 a small chamber 33. A passage 34 is drilled axially through the rod 29 and communicates with the small chamber 33. A single hole 35 of substantially the same diameter as the 30 passage 34 is drilled between the triangular faces of the bit 30 and enters the chamber 33 to communicate with the passage 34. This hole 35 likewise 35 opens eccentrically with reference to the axis of the drill 10 and it is preferred that this hole also opens exteriorly of the bit 30 closely adjacent its axis. It will be observed from Figures 1 to 4, inclusive, and Figure 6, that the angularly directed passages 26, 35 cooperate with the undercut of recess 9 to maintain the entire bottom of the drilled hole clear of stone chips, thereby increasing the drilling speed.

45 When a drill constructed according to my invention is placed in operation, some of the compressed air or other fluid which is exhausted from the power operating mechanism of the drill passes through the passage 25 and thence 50 outwardly through the holes 26 to impinge upon the bottom of the drilled hole 20. The rock dust and chips are thus effectively blown out through the spaces 40 which are formed between the side walls of the drilled hole 20 and the body portion 45 of the bit. By drilling the holes 26 or 55 35 in a manner as described, the bit will effectively drill a hole in the rock without producing any uncut cores of rock such as occurs in constructions wherein the passage 25 opens axially 60 through the bit.

In addition to the illustrated structures, I have considered other modifications to be within the scope of my invention, substantially as defined by the appended claims.

65 I claim:

1. A drill of the rotary-percussive type including a rod having a passage extending therethrough, a bit at one end of said rod, said bit comprising a body portion having a plurality 70 of integral cutting edges at one end thereof terminating beyond the end and radial limits of said body portion, said cutting edges stopping short of such axis to form a central recess in said bit, such recess during operation of said 75 drill constituting an inter-communication for the

spaces formed between said cutting edges, said bit being provided with an aperture for fluid communicating with the passage of said rod and opening exteriorly of the body portion of said bit between the cutting edges thereof and being 5 spaced radially of said central recess.

2. A drill of the rotary-percussive type including a rod having a passage extending therethrough, a bit at one end of said rod, said bit comprising a body portion having a plurality of 10 integral cutting edges at one end thereof terminating beyond the end and radial limits of said body portion, said cutting edges stopping short of such axis to form a central recess in said bit, such recess during operation of said drill constituting an inter-communication for the spaces 15 formed between said cutting edges, said bit being provided with an aperture for fluid communicating with the passage of said rod and opening exteriorly of the body portion of said bit between 20 the cutting edges thereof and being spaced radially of said central recess, such aperture being angularly directed within the radial limits of said cutting edges.

3. A bit for use with a rotary-percussive drill 25 comprising a body portion having a plurality of integral cutting edges at one end thereof terminating beyond the end and radial limits of said body portion, said cutting edges stopping short of such axis to form a central recess in said bit, such recess during operation of said drill bit constituting an inter-communication for the spaces 30 formed between said cutting edges said bit being provided with an aperture for fluid which opens exteriorly of said body portion between the cutting edges thereof and being spaced 35 radially of said central recess.

4. A bit for use with a rotary-percussive drill comprising a body portion having a plurality of integral cutting edges at one end thereof terminating beyond the end and radial limits of said body portion, said cutting edges stopping short of such axis to form a central recess in said bit, such recess during operation of said drill bit constituting an inter-communication for the spaces 40 formed between said cutting edges, said bit being provided with an aperture for fluid which opens exteriorly of said body portion between the cutting edges thereof and being spaced 45 radially of said central recess, such aperture being angularly directed within the radial limits of said cutting edges.

5. A drill of the rotary-percussive type including a rod having a fluid passage extending therethrough, a bit at one end of said rod, said bit comprising a body portion having a plurality of integral cutting edges, the inner ends of the cutting edges terminating short of the longitudinal axis of the drill to provide a central recess in the bit, said recess constituting an inter-communication for the spaces between the cutting edges and an aperture in the bit connected with the passage of said rod, said aperture terminating between the cutting edges of the bit and in spaced relation to the longitudinal axis of 60 the drill.

6. A bit for use with a rotary-percussive drill comprising a body portion having a plurality of integral cutting edges, the inner ends of the cutting edge terminating short of the longitudinal axis of the bit to provide a central recess therein, said recess constituting an inter-communication for the spaces between the cutting edges and an aperture for fluid in said bit terminating between the cutting edges thereof and in 70 75

spaced relation to the longitudinal axis of said bit.

7. A bit for use with a rotary-percussive drill comprising a bit portion having a plurality of integral cutting edges, the inner ends of the cutting edges terminating short of the longitudinal axis of the bit to provide a central recess therein, said recess constituting an inter-communication for the spaces between the cutting

edges, means on the bit arranged to engage the end portion of a drill rod, and a passage having a discharge aperture in said bit terminating between the cutting edges thereof and in spaced relation to the longitudinal axis of said bit, and arranged to communicate with the end portion of said rod for transmitting fluid from the rod to the aperture.

FRANK F. GRAHAM.
